DESIGN FOR A SPARK PLUG

Eugene W. Binkowski, Jersey City, and Jacob V. Loose, North Bergen, N. J.

Application July 1, 1936, Serial No. 63,601

Term of patent 3½ years

To all whom it may concern:

Be it known that we, Eugene W. Binkowski and Jacob V. Loose, citizens of the United States, residing at Jersey City, in the county of Hudson and State of New Jersey, and North Bergen, in the county of Bergen and State of New Jersey, respectively, have invented a new, original, and ornamental Design for a Spark Plug, of which the following is a specification, reference being had to the accompanying drawing, forming part thereof.

Fig. 1 is a side elevational view of a spark plug showing our new design, and

Fig. 2 is a top plan view thereof.

The dominant features of the design are indicated in solid black lines in the Figure 1.

We claim:

The ornamental design for a spark plug, as shown and described.

EUGENE W. BINKOWSKI.
JACOB V. LOOSE.
